J. H. Neumann

ATTORNEY.

UNITED STATES PATENT OFFICE.

MAX STENZLER, OF PHILADELPHIA, PENNSYLVANIA.

CIGAR AND CIGARETTE EXTINGUISHER.

Application filed October 24, 1922. Serial No. 596,655.

To all whom it may concern:

Be it known that I, MAX STENZLER, a citizen of the United States, residing at Philadelphia, in the county of Philadelphia and 5 State of Pennsylvania, have invented new and useful Improvements in Cigar and Cigarette Extinguishers, of which the following is a specification.

The invention relates to a cigar and cigarette extinguisher and the object of the present invention is to improve the construction of cigar and cigarette extinguishers and to provide a simple, practical and efficient device designed for use within an ash tray 10 and adapted to receive the stumps or butts of cigarettes and cigars and capable of extinguishing the same and of preventing the stumps or butts from being scattered or dropped while handling the ash tray.

20 A further object of the invention is to provide a cigar and cigarette extinguishing device of this character, which may be in the form of a ring equipped with openings arranged at intervals and adapted to receive 25 either a cigarette or cigar stump or butt or both when the cigarette stump is a short one.

It is also an object of the invention to provide a cigar and cigarette extinguishing device of this character adapted to be readily removed from an ash tray or receptacle without tilting the same and spilling ashes.

With these and other objects in view the invention consists in the construction and novel combination and arrangement of parts 35 hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawing, in which like characters 45 of reference designate corresponding parts in the several views:—

Figure 1 is a plan view of a cigar and cigarette extinguishing device constructed in accordance with this invention.

50 Figure 2 is a transverse sectional view of the device, showing the same applied to an ash tray.

Figure 3 is a transverse sectional view, 55 illustrating the manner of extinguishing a cigarette stump.

Figure 4 is a similar view showing the manner of extinguishing a cigar stump.

In the accompanying drawing, in which is illustrated the preferred embodiment of the invention, the cigar and cigarette extinguishing device comprises in its construction an open frame 1 which is in the form of a ring but which may be of any other desired configuration to fit an ash tray of the desired form. The open frame is arranged within an ash tray 1^a and is provided at intervals with cigar and cigarette receiving openings consisting of an upper tapered cigar receiving portion 2 and a lower tapered cigarette receiving portion 3, which is connected with the upper cigar receiving portion by an intermediate tapered portion 5, having its walls arranged at different angles from the walls of the upper cigar receiving portion to provide a shoulder or seat for a cigar stump and forming inclined walls for directing the ashes to the lower opening 3 so that ashes will not accumulate within the opening when the cigar stump 6 is placed in the upper cigar receiving portion, as 70 illustrated in Figure 4 of the drawing. The tapered upper portion 2 is adapted to compress and extinguish the cigar stump 6 and the lower cigarette receiving portion 3 is adapted to compress and extinguish a cigarette stump 7, as illustrated in Figure 3 of the drawing. By the particular construction of the openings the device is adapted to receive cigar and cigarette stumps and will extinguish the same and retain the same 75 in the openings to prevent the stumps from being scattered, and the open frame is adapted to be readily removed from the ash tray, an inner lower beveled edge 4 being provided to permit the open frame to be readily grasped and lifted out of the ash tray without inverting the latter and spilling the contents thereof. The outer face of the open frame is preferably tapered, as shown, 80 to fit the inclined wall 8 of the ash tray.

What is claimed is:

1. A cigar and cigarette extinguishing device including an ash tray having a bottom and an upwardly extending wall, and an open marginal frame arranged within the ash tray and fitting the wall thereof and provided at intervals with cigar and cigarette receiving and extinguishing openings and having a horizontal bottom face surrounding the lower ends of the said open- 105
- 110

- ings and supported upon the bottom of the tray which forms a lower end wall for the said openings to prevent down draft there-through and cause an extinguishing of cigars and cigarettes, the lower face of the said frame being beveled at the inner edge beyond the lower ends of the openings to form a hand hold for removing the frame from the tray.
- 10 2. A cigar and cigarette extinguishing device including an ash tray having a bottom and an upwardly extending wall, and an open marginal frame arranged within the ash tray and fitting the wall thereof and provided at intervals with cigar and cigarette receiving and extinguishing openings and having a horizontal bottom face surrounding the lower ends of the said openings and supported upon the bottom of the tray

which forms a lower end wall for the said 20 openings to prevent down draft there-through and cause an extinguishing of cigars and cigarettes, the lower face of the said frame being beveled at the inner edge beyond the lower ends of the openings to 25 form a hand hold for removing the frame from the tray, said openings consisting of an upper downwardly tapered cigar receiving portion, a lower tapered cigarette receiving portion of less diameter than the 30 said upper portion, and an intermediate downwardly tapered portion presenting inclined walls arranged at a different angle from the walls of the said upper and lower portions of the openings.

In testimony whereof I have hereunto set my hand.

MAX STENZLER.
